J. Stimpson.
Car Axle.

Patented Oct. 23, 1834.

James Thompson Baltimore Maryland

Letters Patent

The document appears to be a patent application. The text reads: "The invention appears to be in these Letters Patent and making part of the same and for a description in the words of the said James Thompson himself of his improvement in the running gear of Rail Road Carriages

In all or where this presents shall come: To be it known that I James Thompson of the City and County of Baltimore and State of Maryland, have invented a new and useful improvement in the running gear of Rail Road Carriages and that the following is a full and exact description of the construction and operation of said improvement and how it is improved by me. I make a joint in the center of the axle which jointed axle should always be in the hind carriage when running. This joint I connect by a coupling joint by letting one shaft into the other. and if the former is to be used it may be made in the following or in any other way that may be preferred. I form a rim or flaunch by upsetting the end upon the middle ends of each of the half axles when they meet together and make these flanches in the finish about one and a half inches deep or larger all round than the axle and the same are then more or less and turn them off to an exact size, and face them off to each other and turn the ends a very little concave within or about the base of the rim or flaunch so that they may not touch each other in the center and that the cavity formed may contain oil. These should be turned nearly straight and of a size as far from the center as the coupling is intended to reach. The coupling should be made of two parts divided in the center longitudinally and for the more safety it should be swelled considerably at the center than at the ends or wider than a sufficient thickness to cover the rims or flanches formed on said axles and covering the other portion and the coupling to be held together by strong iron bolts with nuts, or else

may be secured by iron bolts if preferred. Thus when said coupling box is thus closed together, it may be drilled out exactly to fit the size of the axles, on each side of the aforesaid wings or flanges, it should then have a groove turned out within its center of a depth and width sufficient to fit upon both of said wings or flanges when they are placed close together so that there will be no loose play in any part, and that when said coupling box is bolted on closed fast upon said axles, the axle will be as secure from loose play in any direction as though it was solid except that of their being allowed to turn round in different directions in said coupling, or it may be made in any other way if preferred. It will be seen that when running upon a straight road if all the wheels are of equal diameters, which by the by is very seldom the case, there would be no movement of the half axles within the coupling and when running upon a curve, if the axle was two inches and three quarters in diameter and the wheels thirty six, it would then be only no movement as two and three quarters are to thirty six, while the distance the coupling is from the wheel, affords so much room for the wheels by leverage that but a very small degree of stroke within the box can be brought to act upon it. Now let us consider the effect of the effect of the steering power afforded by the box. The hind wheels must yield to the slightest impulse. The consequence upon the forward wheels can direct the course of the carriage with nearly as much ease as though they were running by themselves independent of the carriage, thus steering a direct course with the road and at the same time effecting what was contemplated by the use of a vibrating axle, while it avoids the dangers resulting therefrom & the wheels all made fast to their axles and the axles themselves kept perfectly parallel to each other and thereby avoiding all the injury and risk of property resulting from the application of lone wheels and axes as much of the propelling power on their movements as by keeping away from to make the wheels skip upon the road when all the wheels are made fast to their axles and no front wheel.

Now you might say it would be with this improvement and

as to be as broad as the roads as suspension is now
done in America on Railways and other Rail Roads. No article
exists in itself in use at the present day upon Rail Roads com-
parable with it in usefulness. The beneficial effects
of the joint in one of the axles may be illustrated by considering the fol-
lowing facts which call for an easement to motion after bringing to
mind a fact which will be readily understood by those in the least
acquainted with the subject.

Suppose wheels made fast to two axles which are confined in close boats, far
apart from each other (bearing in mind the law of adhesion the wheels have to the
axles) suppose that all the wheels in front in contact, should always be as
wide as the rear. Supposing then one wheel to be one thousandths of an inch
more than the other, then after a thousandth resolution take place. The three would
be in contact farther than the other equal to their whole circumference if they
all had the same diameter. The small wheel would have to slide that distance upon
the axle and its law of action upon the axle would be equal to the differ-
ence in their diameters which in most cases is as twelve to one. And that
multiplied by the adhesion of the wheel to the soil, which is at least three
hundred pounds the stop upon the axle would be of thirty six hundred
pounds, and if, however it happened to be the case with one wheel, and they
had upon the diagonal corner of the carriage it would go straight ahead
but the extra power required to move it would be equal to that of making the
other wheels stop and this is an evil that will not come in contact
with the difficulty continually for the slipping will not be in contact with
the small wheel. Then looks into view the power
supplied by the moving power. The constant wear and tear of wheels
and say 1/16. The importance of the joint will be more fully comprehended
when you see what points might be acted of great magnitude but
that is another place for a dissertation upon such matters.

Now in the use of experiment to some extent as above described and
in the use of history and anciently useful under various parts of
the world you have and could soon perceive any difference in
the motion of wheels. What follows as near as the applica-

tion of this joint to one of the uses of any description of Rail Road carriages and
Locomotives, whereby to allow the hind wheels to yield to the direction required
to be given by any change in the direction of the Road or to the conical form
of the wheels upon the fore-axle, or any other mode whereby the same object
is obtained by the same principles of action or construction, and also for
all other carriages to which it may be beneficially applied.
